AWNNG

August Bruns, Richmond Hill, Jamaica, N. Y.

Application June 30, 1938, Serial No. 216,720

21 Claims.

(Cl. 156—15)

My invention relates to a new and improved awning.

One of the objects of the invention is to provide an improved awning having a series of metal sections or louvers, said sections being vertically movable relative to the frame of a window or the like.

Another object of the invention is to provide improved means for manipulating said louvers.

Another object of the invention is to provide improved means for holding the louvers in their spaced position so as to prevent rattling.

Other objects are to provide a durable and simple construction which can be readily manufactured and applied.

Fig. 1 is a front elevation showing the improved device applied to a window frame, with the louvers close to each other.

Fig. 2 is a side elevation showing the louvers in their spaced position.

Fig. 3 is a side elevation similar to Fig. 2, showing the sections in their adjacent position.

Fig. 4 is a side elevation, on a larger scale than Fig. 2 and Fig. 3, showing the channel sections adjacent each other, and means for clamping the pins which are connected to the louvers, in order to prevent the parts of the device from rattling.

Fig. 5 is a partial front elevation of Fig. 4.

Fig. 6 is a partial front elevation of the right-hand side of the device.

Fig. 7 is a detail sectional view showing the mechanism for holding the channel sections firmly in clamped position, in order to clamp the pins of the louvers.

Fig. 8 is a section on the line 8—8 of Fig. 9, showing the channel sections spaced from each other so as to release the pins of the louvers.

Fig. 9 is a front elevation of Fig. 8.

While the improved awning device may be applied in any location, it is shown in Fig. 1 as applied to the frame F of a window W.

A pair of spaced vertical channels 1 and 2 are located at the right-hand side of the frame (referring to Fig. 1) so as to form a first vertical guide. A pair of similar spaced channels 3 and 4 are located at the left-hand side of the frame F of the window W, in order to form a second guide.

The channels 1 and 2, and the means accessory thereto, are identical with the channels 3 and 4 and the accessory means thereof.

As shown in Fig. 4 and Fig. 7, arms or box-like brackets 27 are connected to the rear vertical channel 4. These brackets 27 are provided with enlarged heads 27a which are connected to the

rear channel 4 by means of rivets 27b. In the specific embodiment disclosed, three brackets 27 are connected to the rear channel iron 4, but there may be any suitable number of such brackets. As shown in detail in Fig. 7, the front wall of the channel iron 3 is struck out adjacent the brackets 27 so as to form angular projections 31. The front end-walls of the box-like brackets 27 are inclined to the vertical plane. The long arms 10 or webs of the angular projections 31 abut the outer end-walls of the brackets 27, when the channels 3 and 4 are in the clamping position shown in Fig. 4 and Fig. 7. Curved blade springs 29 overlie the projections 31 and are anchored to the inclined front walls of the brackets 27. For this purpose the said walls are provided with tapped openings or recesses. Screws 28 hold the respective leaf springs 29 in position, as shown in Fig. 7. Each screw 28 has a smooth or unthreaded shank 28a, having a reduced inner threaded portion which is screwed into the tapped opening of the front end-wall of the bracket 27. The long arm of each angular portion 31 is provided with a longitudinal slot 30, which is also shown in Fig. 9. The smooth shank of each screw 28 passes through a slot 30. The springs 29 serve to resiliently hold the channel 3 against outward movement with respect to the brackets 27, and thus with respect to the channel 4, as well as to perform other functions hereinafter pointed out. As shown in Fig. 9, the width of each spring 29 is greater than the width of the respective slot 30.

The rear channel irons 2 and 4 are connected to the frame F by any suitable means, such as screws 14a, which are shown in Fig. 4. Therefore the rear channel irons 2 and 4 remain stationary. The front channel irons 1 and 3 are vertically movable, relative to their respective rear channel irons 2 and 4. Identical operating mechanism is used for moving the front channel irons 1 and 3 vertically, relative to their respective rear channel irons 2 and 4. The channel iron 3 is shifted vertically relative to the channel iron 4 by turning an operating arm 34 the specific operation of which will be described hereinafter, but which broadly is as follows: When the operating arm 34 is in the "down" position shown in Fig. 7, the channel irons 3 and 4 are closest to each other so that the space 4a between the adjacent end-walls of said channels 3 and 4 is of minimum width, thus clamping the shanks of the pins 9a between said adjacent end-walls of the channels 3 and 4. In the "up" position of the arm 34 which is shown in Fig. 9, the channel

iron 3 has been shifted laterally relative to the channel iron 4, so as to release the shanks of the pins 9a, thus permitting said pins 9a to move up and down freely in the space 4a.

As shown in Figs. 7 and 8, the channel iron 3 is provided with a U-shaped bracket 35, whose base is connected to said channel iron 3 by means of rivets 36. The bent inner end of the arm 34 passes through a suitable hole which is provided in a side face of the rear channel iron 4. The channel iron 4 is provided with a reinforcing piece 4b in order to provide an additional bearing for the inner bent end of the arm 34. The base of the arm 34 is provided with a U-shaped crank-extension 33, inwardly of the channel iron 4, and said extension abuts the top and bottom arms of the bracket 35. Therefore the channel iron 3 can be shifted vertically relative to the channel iron 4, by turning the arm 34. Similar means are provided for shifting the channel iron 1, relative to the channel iron 2.

Since the front faces of the brackets 27 are inclined outwardly relative to the vertical plane, said inclined faces act as cam members, in combination with the abutting long arms of the angular projections 31, to shift the front channels laterally, when said channels are moved upwardly. As shown in Fig. 8, when the channel 3 is moved upwardly, a part of the long arm of the angular projection 31 rides upon the inclined end-face of the arm 27. Hence in Fig. 8 the bottom edge of the long arm of the angular projection 31 is located intermediate the top and bottom of the outer inclined face of the member 27. The lateral movement of the channel 3 increases the compression of the springs 29, which frictionally hold the channel iron 3 in the upper position shown in Fig. 8, until the arm 34 is turned from the "up" position shown in Fig. 9, to the "down" position shown in Fig. 7. In the "down" position shown in Fig. 7, the compression of the springs 29 is effective to clamp the shanks of the pins 9a tightly between the adjacent end-walls of the channels 3 and 4.

Referring to Fig. 4, the awning comprises a series of louvers or sections 5 which can be made of copper or of copper alloy or other suitable metal or material which may be rusting or non-rusting. The inner and outer surfaces of these louvers 5 may be polished so that they have high reflecting power. These louvers 5 are preferably curved into parabolic shape, although they may have any desired curved shape. The upper end of each louver 5 is turned so as to form a tubular member 6. Short pins 10 fit into the respective ends of each tube 6. The pins 10 of the top louver 5 are fixed suitably to the rear channel irons 2 and 4, respectively. The other pins 10 are slidably located in the spaces between the pairs of channel irons 1 and 2, 3 and 4, respectively, which serve as guides for the up and down sliding movement of said pivot pins 10. If desired, the pins 10 may be dimensioned so that they are clamped between the adjacent end-walls of the respective pairs of channel irons, when said channel irons are in the relative position shown in Fig. 7. If desired, the pivot pins 10 which are below the top pivot pin may be freely slidable between the respective pairs of channel irons, even when said channel irons are in the clamping position shown in Fig. 7.

At its lower end, each louver 5 is turned to

provide a tube 7a. Reinforcing each end of the louvers 5 are wishbone frames 8a having lower arms 8. The apex of each frame 8a is pinned to its respective louver 5 by a pin 7 projecting into a respective tube 7a. The upper rear of each frame 8a is pinned to its respective louver 5 by the hereinbefore described pins 10 projecting into the tubular members 6. At the rear of each arm 8 is a pin 9a extending in a direction parallel to the pins 10 and between the respective pairs of channels 1 and 2, and 3 and 4 as shown in Fig. 4. As explained hereinabove, the pins 10 and 9a cooperate with the pairs of channels to guide the louvers 5 in their up and down movement, and the pairs of channels clamp against the pins 9a to hold the louvers 5 in adjusted position.

When the louvers are in the position shown in Fig. 1 and Fig. 3, adjacent louvers abut and are close to each other. A flexible member 11, which may be a cord or chain or cable, is connected at 11a to the bottom louver 5. As shown in Fig. 5, the flexible member 11 passes around a pulley 20 which is located in a first pulley housing 13. The housing 13 is connected to the frame of the window by means of screws 14. The pulley-housing 13 abuts a second housing 15, whose front wall is connected to the rear wall thereof by means of screws 16. The screws 16 can also enter the frame F of the window. As shown in Fig. 1, the flexible member 11 has a top horizontal run which passes slidably through the second housing 15. The flexible member 11 passes around a second pulley 21 which is pivotally mounted at 22 in a second pulley-housing 17, which is connected by means of screws 18 to the frame of the window. The right-hand vertical run of the flexible member 11 can be wound around a suitable hook or arm 11b. A second flexible member 12 passes around a pulley 23 which is turnably mounted at 24 in the housing 11.

Referring to Fig. 1, the right-hand vertical run of the flexible member 12 is connected to the bottom louver 5 at a point which is on the same horizontal line as the point 11a. The left-hand run of the member 12 is adjacent the right-hand run of the member 11. Hence, the operator can pull downwardly upon the adjacent runs of the members 11 and 12, so as to raise the louvers from the position shown in Fig. 2 to the position shown in Fig. 3 and the adjacent runs of the members 11 and 12 can then be wound around the member 11b. In order to limit the downward movement of the louver, chains or other flexible members 38 are connected to the arms 8 at the points 8a.

In Fig. 1 it may be assumed that the louvers have been raised to their relative top positions, so that the levers 34 can then be turned from the "up" position, to the "down" position, so as to hold the louvers in said inoperative position. Likewise, the channel irons 1 and 3 may be moved to hold the louvers, when the louvers are in the intermediate position shown in Fig. 4.

For convenience, either pair of channel irons may be designated as clamping members or holding members which are movable relative to each other and which are adapted to engage all the louvers. In order to avoid restricting the invention unduly, it covers a structure in which said clamping or holding members will not grip each and every louver. For the purposes of the invention the members 9a may be considered as forming operative parts of the louvers, since the

structure may be varied greatly without departing from the spirit of the invention.

As shown in Fig. 5, each member 9a comprises a shank and two enlarged heads, the diameter of each head exceeding the maximum width of the space 4a, which is shown in Fig. 8. These heads may be detachably connected to the shanks in any suitable manner, so as to permit ready assembly of the members 9a with the channel irons and with the links or rods 8. Each pin 10 is also shown as having an enlarged shoulder which serves as a stop to limit the movement of the shanks of the pins into the tubular members 6. Said shoulders may also be detachably connected to the shanks of the members 10.

When the louvers are in the position shown in Fig. 1, with the handles 34 turned to their "up" or release positions, the louvers are free to fall to the positions illustrated in Fig. 2. This can be controlled by means of the adjacent runs of the horizontal members 11 and 12. The awning can be fully extended to the position as shown in Fig. 2 or it may be partially extended as shown in Fig. 4.

It is clear that I have provided a simple construction which can be made wholly of metal and which is simple and durable.

While the front channels 1 and 3 have been described as biased by the springs 29 to move towards the stationary rear channels, so as to clamp the holding members 9a of the louvers, since the springs 29 abut the long inclined arms of the projections 31, it will be understood that other spring means may be provided for this purpose.

This embodiment shows a series of louvers, namely, two or more. However, the invention also applies to a small awning which would only have two louvers and this is included within the claims whenever I refer to a series of louvers.

For convenience, I have described the device and identified the same in the claims, with reference to the vertical positions of the channel irons. However, the invention is not limited to said vertical position. Likewise, whenever I refer, in the claims, to the inclined front walls of the members 27, I include all equivalent cam means or the like, whereby the vertical movement of the first clamping member 3 relative to the second clamping member 4, will also produce the lateral movement of the first clamping member 3 relative to the second clamping member 4.

The invention is not to be limited to the details of the preferred embodiment, as numerous changes and omissions can be made without departing from the spirit of the invention.

I claim:

1. In an awning, a louver having a follower member, a first vertical and vertically movable clamping member, a second vertical and stationary clamping member spaced laterally from the first clamping member, said follower member being mounted to move vertically between said clamping members, the second clamping member having a laterally projecting cam member having a front face which is inclined outwardly to the vertical plane, the wall of the first clamping member having an inclined wall-portion which substantially abuts said front face when the lateral space between said clamping members is of predetermined minimum width, said clamping members being then located to hold said follower member against movement, a screw having a head, said screw having a shank which passes through a slot in said inclined wall-portion, the threaded end of said screw engaging

15 said front face, said first clamping member being movable relative to the said shank, a spring between said head and said inclined wall portion, and adapted to urge said first clamping member towards said second clamping member, and turnable means constructed to move the first clamping member up-and-down relatively to the second clamping member, said turnable means having a portion projecting beyond a side of said 20 first vertical member, said cam and said wall-portion being shaped to move the first clamping member laterally away from the second clamping member when the first clamping member is moved vertically relatively to the second clamping member.

2. An awning device comprising a first pair of first upstanding members at the left-hand side of said device and a second pair of second upstanding members at the right-hand side of said 25 device, each said pair having one of its upstanding members located behind the other upstanding member of said pair, one upstanding member of each pair being vertically movable relative to the other and stationary upstanding member of the respective pair, a series of superposed louvers, the top louver having its upper edge connected to fixed means, the tops of the other louvers having their upper ends connected to supplemental means, said supplemental means being located between said pairs of upstanding members and being vertically slidably relatively to said pairs of upstanding members, arms connected at their outer ends to the lower ends of said louvers, the inner ends of said arms being 30 connected to studs, said studs being located between said pairs of upstanding members and being vertically slidably relative to said pairs of upstanding members when the upstanding members of each pair are spaced apart predetermined distances, said studs being spaced laterally outwardly relative to said supplemental means, the stationary upstanding member of each pair and the respective movable upstanding member having cooperating cam means constructed to move 35 the vertically movable upstanding member of each pair towards the stationary upstanding member of the respective pair when the movable upstanding member is moved vertically relatively to the stationary member so as to clamp said studs between the pairs of upstanding members.

3. In an awning, blind or the like of the type described, a guiding and supporting framework, at least three louvers supported for up and down movement in the same path, said louvers being 40 vertically disposed and angularly inclined, following means, operatively associated with said framework, connected to the inner upper edges of said louvers for guiding the same in a common vertical path, a rigid structure supporting the outer and lower edges of said louvers and maintaining the angularity of said louvers, said structure having following means operatively associated with said framework, and separate track means for said louver connected following means and said structure, said track and following means being spaced to permit non-interfering movement of said following means, said louvers and louver supporting and guiding means being 45 proportioned to nest one within the other.

4. In an awning, blind or the like of the type described, a framework comprising sides, each of said sides having horizontally spaced vertically extending track portions, at least three louvers 50 disposed one above the other in a common path

and adapted to be raised and lowered into and out of nested position, said louvers being inclined, and means connected to said louvers for guiding the upper inner edges of said louvers along one of the track portions of each of said sides, means connected to said louvers for defining and maintaining the inclination of said louvers and operating in the other of said track portions, said means operating in said track portions being in a laterally offset relation so as to permit nesting of said louvers and maintain said louvers with a constant inclination in and out of nested position.

5 5. In an awning, blind or the like of the type described, a framework comprising side portions, each of said side portions on opposite sides thereof having vertical longitudinally extending portions in spaced relation defining a pair of tracks, at least three louvers supported for up and down movement into and out of nested position in the same common path, and means connected with 10 said louvers for guiding the inner and outer edges of said louvers and maintaining the inclination thereof in all positions, said means operating in said tracks.

6 6. A louver adapted to be guided for up and down movement into and out of nesting arrangement with similar louvers, comprising a relatively rigid body portion having generally trapezoidal shape, means for maintaining said louver in a substantially constant angular position with reference to a horizontal plane, and substantially vertical guiding and supporting means located adjacent the corners of said body in laterally offset relation to each other to permit nesting with similar louvers.

7 7. In an awning, blind or the like of the type described, a framework, plural guideways defined in said framework, at least three louvers supported for up and down movement in said guideways, said louvers including means operating in 15 said guideways and holding said louvers in positions of substantially constant inclination during up and down movement in said guideways, said louvers and their associated guiding means being constituted as a unitary structure and being 20 of a shape and configuration to permit nesting.

8 8. In a construction of the type described, a pair of spaced frame members, spaced longitudinal edge portions constituting a part of each of said frame members and defining parallel guideways therein in offset relation, at least three louvers disposed between said frame members, and guiding and supporting means for said louvers attached at the ends thereof and operating in said guideways to support said louvers in 25 adjusted positions along said guideways, said means at each of said louvers being in offset relation with one another, whereby said louvers may be nested.

9 9. In an awning, blind or similar construction, a pair of spaced frame members each having vertical guideways defined therein, at least three louvers supported in said guideways for up and down movement, said louvers being inclined with their upper inner edges located between said 30 frame members, means guiding said upper inner edges in said guideways, and guiding means for engaging with said guideways and supporting said louvers in positions of substantially constant inclination with reference to a horizontal plane, the lower outer edges of said louvers being wider than said upper edges, said first and second means being in a laterally offset relation to permit said louvers to nest.

10 10. In an awning or blind construction or the

like, frame members each defining a pair of vertical guideways in offset relation, at least three louvers adapted to be guided and supported in said guideways for up and down movement, and means upon said louvers and operating in said guideways, said means being in similar offset relation, whereby said louvers may nest.

11 11. In an awning device, at least three awning members, means for guiding said awning members along a common path into and out of nesting relation, means for supporting said awning members in definite spaced relation and out of nesting relation, members at opposite ends of said awning members for supporting and guiding said awning members and for maintaining said awning members in fixed angular relation to a horizontal plane, track means within which said members operate, said members being offset from each other so as to enable the nesting of the awning members.

12 12. In an awning, blind or similar structure having at least three angularly disposed louvers guided and supported for vertical movement into and out of nested relation, guiding structure for said louvers comprising inner and upper follower members at each end of each louver for guiding the tops thereof, vertical guideways at opposite ends of said louvers with which said follower members coat, outer and lower follower members at each end of each louver for maintaining the angularity of each louver, additional vertical guideways adjacent said first guideways with which said outer and lower follower members coat, said respective guideways and associated follower members being in a laterally offset relation so as to enable substantially complete nesting of the louvers.

13 13. An awning device, comprising an awning member, means on opposite ends of said awning defining guideways, follower means upon said awning member operating in said guideways, means for adjustably supporting said awning member at a plurality of operative points along said guideways, and means for clamping said follower members against movement at all positions of adjustment along said guideways.

14 14. An awning device, comprising side frames in the form of spaced channel members defining guideways, a plurality of awning members having follower means at their opposite ends operating in said guideways, means for supporting said members in different operative positions of adjustment along said guideways, said channel members being movable relatively to each other, and means for selectively effecting relative movement between said channels so as to vary the spacing thereof to clamp said followers against movement in different positions of adjustment of said awning members.

15 15. In an awning device, a plurality of superimposed awning members, means constituting a common guiding track for said awning members for up and down adjustment, and means for simultaneously locking said awning members in different operative positions of adjustment along said track.

16 16. In an awning device, the combination with a plurality of awning members freely movable along a common track, of locking mechanism extending along adjacent the path of movement of said members, means for supporting said members in different positions of adjustment, and means for engaging said awning members with said locking means, at will, for simultaneously locking the same in a plurality of operative posi-

tions of adjustment along their path of movement.

17. A device of the character described for supporting and guiding awnings or the like having laterally projecting guiding portions, which comprises a structure at each side of said awning or the like, each structure comprising a pair of members one being fixed and the other being movable, said members being spaced apart to provide a channel in each structure, respectively, for receiving said guiding portions, operative structure for moving each movable member toward its associated fixed member and against said guiding portions, in any position of adjustment of said guiding portions, and spring means for resiliently holding each movable member against said guiding portions.

18. A device of the character described for supporting and guiding awnings or the like having laterally projecting guiding portions, which comprises a structure at each side of said awning or the like, each structure comprising a pair of members one being fixed and the other being movable, said members being spaced apart to provide a channel in each one of said structures, respectively, for receiving said guiding portions, said movable members being mounted for movement toward and away from said fixed members and also longitudinally with respect to said fixed members, camming means associated with said movable members for camming said movable members toward said fixed members into clamping relation with said guiding portions, in any position of adjustment of said guiding portions, operative structure for actuating said camming means, and means for resiliently holding said movable members against said guiding portions.

19. A device of the character described for supporting and guiding awnings or the like having laterally projecting guiding portions, which comprises a structure at each side of said awning or the like, each structure comprising a pair of members one being fixed and the other being

movable, said members being spaced apart to provide a channel in each structure, respectively, for receiving said guiding portions, mechanism including a lever pivotally mounted in each fixed member and operatively associated with each movable member, respectively, for moving each movable member towards its associated fixed member and against said guiding portions, in any position of adjustment of said guiding portions, and spring means for resiliently holding each movable member against said guiding portions.

20. A device of the character described for supporting and guiding awnings or the like having laterally projecting guiding portions, which comprises a spaced structure at each side of said awning or the like, each structure comprising a pair of members one being fixed and the other being movable, said members being spaced apart to provide a channel in each one of said structures, respectively, for receiving said guiding portions, said movable members being mounted for movement toward and away from said fixed members and also longitudinally with respect to said fixed members, camming means associated with said movable members for camming said movable members toward said fixed members into clamping relation with said guiding portions, in any position of adjustment of said guiding portions, and mechanism including a crank pivoted in each fixed member for actuating said camming means.

21. In an awning or blind construction or the like, at least three relatively rigid louvers, plural guideway means for supporting said louvers for relative up and down movement, guiding and supporting means upon said louvers operating in said guideways to support said louvers constantly in similar positions in all positions of adjustment, the shape and configuration of said guiding and supporting means enabling said louvers to nest one within the other.

AUGUST BRUNS.

CERTIFICATE OF CORRECTION.

Patent No. 2,256,609.

September 23, 1941.

AUGUST BRUNS.

It is hereby certified that error appears in the printed specification of the above numbered patent requiring correction as follows: Page 3, second column, line 66, claim 3, after the word "structure" and before the comma insert --following means--; and that the said Letters Patent should be read with this correction therein that the same may conform to the record of the case in the Patent Office.

Signed and sealed this 18th day of November, A. D. 1941.

Henry Van Arsdale,
Acting Commissioner of Patents.
